E. J. MARTIN & E. TAYLOR.
Machine for Cleaning and Smoothing Silk
and other Threads.

No. 233,156.

Patented Oct. 12, 1880.

UNITED STATES PATENT OFFICE.

ELISHA J. MARTIN, OF ROCKVILLE, AND EDWARD TAYLOR, OF WAREHOUSE POINT, CONNECTICUT; SAID TAYLOR ASSIGNOR TO THE LEONARD SILK COMPANY, OF WAREHOUSE POINT, CONNECTICUT.

MACHINE FOR CLEANING AND SMOOTHING SILK AND OTHER THREADS.

SPECIFICATION forming part of Letters Patent No. 233,156, dated October 12, 1880.

Application filed December 10, 1879.

To all whom it may concern:

Be it known that we, ELISHA J. MARTIN, of Rockville, in the county of Tolland, and EDWARD TAYLOR, of Warehouse Point, in the county of Hartford, and State of Connecticut, have invented certain new and useful Improvements in Machines for Cleaning and Smoothing Silk and other Threads; and we do hereby declare that the following is a full, clear, and exact description thereof, whereby a person skilled in the art can make and use the same, reference being had to the accompanying drawings, and to the letters of reference marked thereon.

15 Like letters in the figures indicate the same parts.

Our improvements relate to such machines as are intended for the purpose of removing any projecting fibers from the thread after it 20 is spun, and for cleaning, polishing, and finishing the thread ready for use.

Our invention has for its object the more rapid and perfect accomplishment of the cleaning and smoothing process, and the simplification of the machinery by which it is performed; and it consists in the construction and arrangement of the mechanical devices 25 which will be hereinafter described.

In the accompanying drawings, Figure 1 is 30 a side view of a machine embodying our improvements. Fig. 2 is a top view of the same.

A is the frame of the machine. B is a box carrying the cleaning-spindles C, &c. D is a bobbin containing the silk or thread which is 35 to be cleaned and finished.

E is a roller, around which the thread passes one or more times. The friction of this roller regulates the tension upon the thread, and is adjusted by a central screw or other common 40 device to give it the proper resistance.

The thread passes around the spindles C C C, making several turns around each one, three being the number of turns usually employed, but a greater or less number may be used. The thread then passes onto the roller 45 F, around which it also makes several turns, and which may be called the drawing-roller, as it gives the motion to the thread. This roller receives its motion by a belt from a pul-

ley upon the main shaft, which gives motion 50 to the machine.

G is the bobbin which takes up the silk or other thread after it has passed through the cleaning process. It receives its motion from a friction-pulley, upon which it rests, so that 55 its circumference has a tendency to run a little faster than that of the roller F. This keeps the thread always tight. For this purpose the axes of the bobbin G move in grooves in the frame of the machine, and it is furnished with a weighted roller, H, which runs upon the circumference of the friction-pulley I, which communicates motion to it. This pulley I is driven by a belt from the main shaft, and at such a speed that the circumference 60 will slip a little upon the roller H in keeping the tread tight.

J is a pulley upon the main shaft, which communicates motion to the pulleys F and I by means of belts, as before described.

70 The spindles C, &c., have bearings within the box B, as shown in the drawings.

It is designed to have a series of the machines hereinbefore described arranged side by side upon the same frame and driven by 75 the same main shaft, so that a great number of threads can be operated upon at the same time. The number of cleaning-spindles can also be varied to suit different kinds of threads, eight being a suitable number for ordinary 80 silk.

The operation of our improved machine is as follows: The thread being placed upon the machine as described, the roller F draws it off from the bobbin D and revolves the roller E 85 and the spindles C, and as fast as it is drawn forward it is taken up by the bobbin G. The thread is cleaned and finished by the operation of the spindles. The coils of thread roll upon the projecting fibers of the adjacent coils 90 and cut them off or detach them from the body of the thread in such a manner as to leave them clean and smooth.

What we claim as our invention is—

1. The combination of a series of stationary 95 cleaning-spindles, C, with the tension-roller E and the drawing-roller F, substantially as herein described.

2. The combination of the drawing-roller F, the winding-bobbin G, and the friction-pulley I, with a pulley, J, upon the main shaft, constructed and arranged so that the circumference of the bobbin tends to turn faster than the drawing-roller to keep the thread tight, substantially as herein described.

3. The combination of an independent drawing-roller, F, with the stationary spindles C

and the winding-bobbin G, substantially as so herein set forth.

ELISHA J. MARTIN.
EDWARD TAYLOR.

Correction for Letters Patent No. 233,156.

It is hereby certified that at the time Patent No. 233,156 was granted to Elisha J. Martin (and the Leonard Silk Company (said Leonard Silk Company, assignees of Elisha J. Martin and Edward Taylor, joint inventors) with Martin) for an Improvement in "Machines for Cleaning and Smoothing Silk and other Threads," there was on record in this Office (Liber P24, page 230) an assignment from said Martin of his entire interest to Milo M. Belding of Brooklyn, N. Y., Hiram H. Belding of Chicago, Ill., and Alvah N. Belding of Rockville, Conn., and that the Patent should have been issued to said assignees jointly with the assignees of Taylor; that the correction has been made in the file and papers relating to the case and is hereby made in said Letters Patent to make the title therein conform to the record of the Office.

Signed, countersigned, and sealed this 31st day of December, A. D. 1880.

[SEAL.]

C. SCHURZ,
Secretary of the Interior.

Countersigned:

E. M. MARBLE,

Commissioner of Patents.
